UNITED STATES PATENT OFFICE

2,505,873

RECEIVER FOR PNEUMATIC CARD STRIPPERS AND THE LIKE

Charles E. White, Abington, Mass., and Fred H. White, Charlotte, N. C., assignors to Abington Textile Machinery Works, Abington, Mass., a trust of Massachusetts

Application January 31, 1948, Serial No. 5,554

15 Claims. (Cl. 19—75)

1

This invention relates to improvements in receivers employed in a suction system, for stripping material accumulated upon the cylinder or cylinders of a carding machine or for cleaning other textile cleaning machinery, in which the fibres are separated in the receiver from the dust and are available for use in the manufacture of textile material.

More specifically the invention relates to receivers of the type having a vertical hermetically closed casing divided into an upper fibre-collecting chamber having a screen wall or wall section and a lower dust-receiving chamber communicating with the fibre-collecting chamber through the screen and desirably having in the dust-receiving chamber a filter through which suction is applied to maintain the desired degree of vacuum in the dust-receiving and fibre-collecting chambers.

The fibre and dust-laden air is drawn by said suction into the fibre-collecting chamber through a flexible conduit having a head or heads adapted to be movably positioned in effective proximity to the card cylinder or cylinders, or to the mechanism of other textile machines so as to enable the suction to remove the fibres and dust accumulated thereon.

In usual machines of this type the wall of the fibre-collecting chamber and of the dust-receiving chamber are respectively provided with doors which are hermetically sealed by suitable clamping means which must be released to permit the door to be opened and the contents removed from the respective chambers.

Inasmuch as the fibres accumulate rapidly in the fibre-collecting chamber it is necessary to open this door frequently. This necessitates the presence of an operator to open the door and remove the fibres from the fibre-collecting chamber and then to close and seal the door. The delay in the operation of the suction system thus caused, which is increased by the time required after the resumption of the operation of the suction mechanism to provide the desired degree of partial vacuum in said chambers, seriously interferes with the proper timing of the pneumatic card stripping mechanism.

Where means are provided for actuating the card stripping mechanism continuously to strip the carding cylinders of a carding machine in successively repeated cycles the entire operation of the carding machine must be discontinued while the fibre is being removed from the fibre-collecting chamber, thus greatly reducing the output of the carding machine.

The general object of the present invention is

2

to provide means for avoiding the delays above described, and thereby to increase the efficiency of the carding apparatus, the uniformity of the product, and the output of the machine, and also to eliminate the presence of an operator to manually remove the fibres in the fibre-collecting chamber, thus materially reducing the cost of production.

One of the objects of the invention is to provide means for progressively delivering the fibre from the fibre-collecting chamber without substantially varying the desired uniform degree of partial vacuum maintained in the fibre-collecting and dust-receiving chambers of the receiver.

Another object of the invention is to provide a discharge conduit, leading from the fibre-collecting chamber through and beyond a wall of the receiver, and having means therein for progressively forcing the fibres therethrough and having means for so resisting the delivery of the fibres from the outlet end thereof as to compact them sufficiently to prevent the entrance of enough outside air at atmospheric pressure through them to substantially vary the desired uniform degree of partial vacuum maintained in said chambers.

A further object of the invention is to provide means for so adjusting the amount of resistance to the passage of the fibres through the discharge conduit as properly to compact fibres of different materials of different characteristics, such as quality, length, etc., sufficiently to prevent the entrance of enough outside air therethrough to vary substantially the desired degree of vacuum maintained in the fibre-collecting and dust-receiving compartments.

These and other objects and features of the invention will appear more fully from the following description and the accompanying drawings and will be particularly pointed out in the claims.

Illustrative embodiments of the invention are shown in the drawings, in which:

Fig. 1 is a view, mainly in diametrical longitudinal vertical section, of a receiver embodying the invention;

Fig. 2 is a vertical sectional view on a reduced scale on lines 2—2 Fig. 1;

Fig. 3 is a horizontal sectional view on lines 3—3 Fig. 1;

Fig. 4 is a diametrical vertical sectional view of a receiver embodying a modified form of the invention; and,

Fig. 5 is an enlarged vertical sectional view on lines 5—5 Fig. 4.

The invention comprises broadly a vertical hermetically sealed casing having an upper fibre-

collecting chamber provided with a screen wall or wall section and having therebeneath a downwardly converging bottom communicating with the tubular discharge conduit extending through a wall of the receiver and providing beneath said bottom a dust-receiving chamber, means for admitting the fibre and dust-laden air into the fire-collecting chamber, means for applying suction through the dust-receiving chamber, thence through the screen wall and the fibre-collecting chamber and a usual flexible conduit to a suction head which is adapted to be placed in proximity to the cylinder or cylinders of the carding machine to be stripped or in proximity to the mechanism upon which dust and fibre are to be removed.

The receiver shown in Fig. 1 comprises a preferably vertical hermetically sealed casing 1 having a base 2 supported upon suitable columns 3 and a dome-shaped top 4 having a screen wall 5 hermetically clamped between the dome-shaped top and the upper end of the vertical cylindrical wall 1. The casing is divided by a suitable downwardly converging partition 6 communicating with a vertical discharge conduit 7 mounted upon the base 2 of the receiver and surrounding an outlet 8 in the base 2, thus dividing the receiver into upper fibre-collecting chamber 9 and a lower dust-receiving chamber 10 therebeneath. The dust-receiving chamber preferably has suitably mounted therein a removable cylindrical filter 11 one end of which communicates with a pipe 12 through which suction is continuously applied by usual air-exhausting mechanism which need not be shown.

As illustrated in Fig. 1 a pipe 13, which extends through the screen 5 at the upper end of the fibre-collecting chamber and through the dome 4, is connected by a suitable union 14 to a usual flexible suction pipe 15 which is provided with a suction head adapted to be moved into proximity to the surface of the cylinder or cylinders of a carding machine or to other machinery, from which the dust or waste material accumulating thereon is to be removed. The means for applying suction from the partial vacuum in the dust-receiving chamber through the fibre-collecting chamber to the suction pipe 15 as illustrated in Figs. 1 and 3 of the drawings comprises a pipe 16 leading vertically from the dust-receiving chamber 10 to a horizontal section 17 having unions 18 and 19 communicating respectively with vertical sections 20 and 21 which are mounted upon the dome 4 and communicate through apertures therein with the chamber of the receiver above the screen 5.

By reason of this construction the suction applied to the dust-receiving chamber produces a partial vacuum in the casing above the screen 5 and through it in the fibre-collecting chamber and through the pipes 16 and 15 to the suction head thereon, thus causing the fibre and dust-laden air to be drawn into the fibre-collecting chamber in which the fibre drops upon the inclined bottom 6 and descends by gravity toward and into the discharge conduit 7.

A vertical reciprocable plunger is mounted within the fibre-collecting chamber and it has a head extending into the discharge conduit which upon downward movement serves to force the material accumulating in the fibre-receiving chamber progressively through the conduit 7, and suitable means are provided at the outlet of the discharge conduit for so resisting the passage of fibre therethrough as to condense it

sufficiently to prevent the entrance of enough outside air to substantially reduce the desired degree of uniform partial vacuum in the dust-receiving and fibre-collecting chambers.

The downwardly converging bottom of the fibre-collecting chamber may be of any suitable character. As illustrated herein it converges toward the vertical wall of the casing preferably to a point beneath the doorway 22 where it communicates with the discharge conduit 7 as illustrated in Fig. 1 of the drawings. The plunger 23, which is mounted in bearings 24 and 25 in brackets 26 and 27 secured to the casing above and below the doorway, is provided with a suitable head 28 extending into the discharge conduit 7 which is provided with means for effectively engaging the fibres which have accumulated upon the bottom 6 of the fibre-collecting chamber and have descended toward and into the discharge conduit 7.

As illustrated herein the head has a plurality of downwardly and outwardly extending arms 29 providing a forked extension which upon downward reciprocation of the plunger will condense the fibres forced by it through the discharge conduit 7. A suitable housing 30, which is secured at its upper and lower ends to the wall of the casing above and below the doorway, prevents fibres and dust from accumulating in the plunger and its operating means.

For convenience in assembling, the mechanism for actuating the plunger is mounted upon a door 31 which covers the doorway 22 and is normally permanently secured to the casing but adapted to be removed for the purpose of assemblage of the plunger with its reciprocating mechanism.

In the construction illustrated herein for actuating the plunger, the plunger is provided substantially centrally of its length with a horizontal slotted portion 32, Fig. 2, which is engaged by the arm 33 of a crank 34 the shaft 35 of which extends through a bearing 36 mounted centrally of the length of the door 31 and through a bearing 37 at the upper end of an arm 38 of a bracket 39 which is mounted upon the door 31.

Any suitable means may be provided for actuating the crank. As illustrated in Fig. 1 the shaft 35 is driven through suitable reducing gear train 40 from the shaft of a motor 41 which is mounted upon a horizontal base 42 integral with the bracket 39 and its arm 38. Suitable means are provided for resisting the passage of the fibres forced downwardly by the plunger 29 through the outlet thereof. As illustrated in Fig. 1 the means comprises a valve 43 which extends across the outlet 8 and is hingedly connected to a bracket 44 mounted upon the casing at the lower end thereof. Suitable means are provided for so adjusting the valve 43 as to produce the desired resistance to the passage of the fibre through the discharge conduit 7 to condense the fibres in the conduit sufficiently to prevent the entrance of enough air through the fibres to substantially vary the degree of vacuum maintained in the dust-receiving chamber by the suction pipe 15. As illustrated the valve 43 is provided with an arm 45 upon which a counterweight 46 is adjustably mounted.

It is obvious from the above description and illustration that by reason of the present construction the reciprocating plunger will progressively condense and discharge the fibres which have accumulated in the fibre-collecting chamber without the necessity of the attendance of

an operator to remove the fibres from the fibre-collecting chamber and will also enable the stripping mechanism to be continuously operated. Where a carding machine is provided with means for successively stripping the cylinders thereof in successive cycles a uniform lap of carded material will be continuously removed from the carding cylinder and continuously taken by the receiver. Hence the interruptions heretofore caused by the shutting down of the suction system during the stripping operation are eliminated and the efficiency and output of the machine are greatly increased and the cost of operation reduced.

Another embodiment of the invention is illustrated in Figs. 4 and 5. In this construction the receiver comprises a casing 47, similar to that illustrated in Fig. 1 except that its lower end is provided with an angle bar 48 which surrounds the lower end of the casing and rests upon the floor and in that the bottom 49 of the casing is spaced from the floor. The upper end of the casing 47 is provided at its upper end with a dome 50 with a screen 51 clamped between it and the upper end of the casing 47. A conduit 52, similar to the conduit 13, extends centrally through the screen 51 and the dome 50 and is connected to a suction pipe, similar to the flexible pipe 15, Fig. 1, and provides means for transmitting the fibre and dust-laden air from the usual suction head into the fibre-collecting chamber 53 as above described.

The fibre-collecting chamber in the construction shown in Fig. 4 comprises a supplemental casing within and concentrically of the casing 47 having an upper section provided with a vertical wall 54 and a downwardly converging wall section 55 which communicates at its lower end with a horizontal cylindrical discharge conduit 56 extending through and well beyond the wall 47 of the receiver. The space between the walls of the supplemental casing forming the fibre-collecting chamber and the walls 47 and 49 of the casing provides a lower dust-receiving chamber 57. An annular passage 58 around the screen 51, or suitable apertures therethrough, establishes communication between the dust-receiving chamber 57 and the space between the dome 50 and through the screen 51 with the fibre-collecting chamber. A cylindrical filter 59, similar to the filter 11 shown in Fig. 1, is provided in the lower portion of the dust-receiving chamber and communicates at its end with a fitting 60 which extends through and is mounted in the wall 47 of the casing and has secured to it a suction pipe 61 which leads to suction-producing means for maintaining a desired constant partial vacuum in the dust-receiving and fibre-collecting chambers and in the flexible pipe leading to the suction head, as above described. A helical propelling screw 62 extends longitudinally of and fits the cylindrical discharge conduit having a shaft 63 which is mounted in aligned bearings 64 and 65 in the end of the conduit 56 and upon the wall 47 of the receiver and is provided with suitable means for rotating the screw in a direction to force the fibres descending from the fibre-collecting chamber into the conduit.

Means are provided for rotating the propeller screw shaft 63 which, as illustrated herein, comprises a pulley upon the shaft 63 adapted to be driven by a power producing means. Any suitable means may be provided for so resisting the passage of the fibres forced through the discharge conduit 56 by the propeller screw as to

condense them sufficiently to prevent the admission of enough air through the fibres to materially vary the predetermined uniform degree of partial vacuum maintained in the dust-receiving chamber, the fibre-collecting chamber, and the pipe through which the fibre and dust-laden air is drawn by suction into the fibre-collecting chamber.

As illustrated in Fig. 4 the propelling screw terminates a suitable distance from the end of the discharge conduit 56 and a suitable adjustable valve is mounted upon the end of the conduit which, as illustrated herein, comprises a valve 66 hinged upon the outlet end of the conduit and provided with an arm 67 having thereon an adjustable counterweight 68 similar to the valve construction illustrated in Fig. 1 and operating in the manner heretofore described.

It will be understood that the particular embodiments of the invention shown and described herein are of an illustrative character and that various changes in construction and arrangement of parts may be made within the spirit and scope of the following claims.

Having thus described the invention, what is claimed as new, and desired to be secured by Letters Patent, is:

1. Apparatus for progressively delivering fibre from a receiver, for a pneumatic card stripper or the like, having a fibre-collecting chamber and a dust-receiving chamber having screened communication therewith, means for admitting fibre and dust-laden air into the fibre-collecting chamber, and means for exhausting air from the dust-receiving chamber to maintain a substantially uniform degree of partial vacuum in said chambers, which apparatus comprises a tubular discharge conduit communicating with said fibre-collecting chamber and having a restricted outlet and continuously operating means for compacting the fibre in said discharge conduit with force sufficient so to condense the fibres therein as to prevent entrance of enough air therethrough to reduce substantially the uniform degree of partial vacuum maintained in said chambers.

2. Apparatus for progressively delivering fibre from a receiver, for a pneumatic card stripper or the like, having a fibre-collecting chamber and a dust-receiving chamber having screened communication therewith, means for admitting fibre and dust-laden air into the fibre-collecting chamber, and means for exhausting air from the dust-receiving chamber to maintain a substantially uniform degree of partial vacuum in said chambers which apparatus comprises a tubular discharge conduit communicating with said fibre-collecting chamber, continuously operating means for progressively forcing fibre from the fibre-collecting chamber through said discharge conduit, and a yieldable valve for the outlet end of said discharge conduit adapted to resist the passage of fibre therethrough so to condense the fibre therein as to prevent entrance of enough air therethrough to reduce substantially the uniform degree of partial vacuum maintained in said chambers.

3. Apparatus for progressively delivering fibre from a receiver, for a pneumatic card stripper or the like, having a fibre-collecting chamber and a dust-receiving chamber having screened communication therewith, means for admitting fibre and dust-laden air into the fibre-collecting chamber, and means for exhausting air from the dust-receiving chamber to maintain a substantially uniform degree of partial vacuum in said

chambers which apparatus comprises a tubular discharge conduit communicating with said fibre-collecting chamber, continuously operating means for progressively forcing fibre from the fibre-collecting chamber into said discharge conduit, and a yieldable valve for the outlet end of said discharge conduit, and means for varying the pressure exerted on said valve and to resist the passage of fibre sufficiently so to condense it as to prevent the entrance of enough air therethrough to reduce substantially the uniform degree of partial vacuum maintained in said chambers.

4. Apparatus for progressively delivering fibre from a receiver, for a pneumatic card stripper or the like, having a fibre-collecting chamber and a dust-receiving chamber having screened communication therewith, means for admitting fibre and dust-laden air into the fibre-collecting chamber, and means for exhausting air from the dust-receiving chamber to maintain a substantially uniform degree of partial vacuum in said chambers which apparatus comprises a tubular discharge conduit communicating with said fibre-collecting chamber, continuously operating means for progressively forcing fibre from the fibre-collecting chamber into said discharge conduit, a valve pivotally mounted on the outlet end of said conduit, and adjustable means for so varying the pressure applied thereto as to resist the passage of fibre therethrough sufficiently to condense the fibre to prevent entrance of enough air therethrough to reduce substantially the uniform degree of partial vacuum maintained in said chambers.

5. Apparatus for progressively delivering fibre from a receiver, for a pneumatic card stripper or the like, having a fibre-collecting chamber and a dust-receiving chamber having screened communication therewith, means for admitting fibre and dust-laden air into the fibre-collecting chamber, and means for exhausting air from the dust-receiving chamber to maintain a substantially uniform degree of partial vacuum in said chambers which apparatus comprises a tubular discharge conduit communicating with said fibre-collecting chamber, continuously operating means for progressively forcing fibre from the fibre-collecting chamber into said discharge conduit, a valve pivotally mounted on the outlet end of said conduit having an arm provided with a counterweight adjustably mounted thereon adapted to vary the pressure applied to said valve to resist the passage of fibre through said outlet with a force so to condense the fibres as to prevent entrance of enough air therethrough to reduce substantially the uniform degree of partial vacuum maintained in said chambers.

6. A receiver for the fibre and dust-laden air of a pneumatic stripper for a carding machine or the like comprising a vertical hermetically sealed casing having an upper fibre-collecting chamber provided with a screen wall and having therebeneath a downwardly converging bottom communicating with a tubular discharge conduit and providing below said bottom a dust-receiving chamber, means for admitting the fibre and dust-laden air into said fibre-collecting chamber, means establishing communication between the dust-receiving chamber and the fibre-collecting chamber through said screen, means for applying suction to said dust-receiving chamber to maintain a desired substantially uniform degree of vacuum in said chambers, continuously operating means for progressively forcing the fibres accumulating in said fibre-collecting chamber through

said tubular discharge conduit with sufficient pressure so to condense the fibres as to prevent the entrance of enough air therethrough to substantially reduce the uniform degree of partial vacuum maintained in said chambers.

5. A receiver for the fibre and dust-laden air of a pneumatic stripper for a carding machine or the like comprising a vertical hermetically sealed casing having an upper fibre-collecting chamber provided with a screen wall and having therebeneath a downwardly converging bottom communicating with a tubular discharge conduit and providing below said bottom a dust-receiving chamber, means for admitting the fibre and dust-laden air into said fibre-collecting chamber, means establishing communication between the dust-receiving chamber and the fibre-collecting chamber through said screen, a filter in said dust-receiving chamber, means for applying suction through said filter to said dust-receiving chamber to maintain a desired substantially uniform degree of vacuum in said chambers, continuously operating means for progressively forcing fibres accumulating in said fibre-collecting chamber through said tubular conduit, and adjustable means at the outlet end of said conduit acting so to resist passage of fibres forced therethrough as to condense them sufficiently to prevent admission through them of enough air to substantially reduce the uniform degree of vacuum maintained in said chambers.

8. A receiver for the fibre and dust-laden air of a pneumatic stripper for a carding machine or the like comprising a vertical hermetically sealed casing having an upper fibre-collecting chamber provided with a screen wall and having therebeneath a downwardly converging bottom communicating with a tubular discharge conduit and providing below said bottom a dust-receiving chamber, means for admitting the fibre and dust-laden air into said fibre-collecting chamber, means establishing communication between the dust-receiving chamber and the fibre-collecting chamber through said screen, a filter in said dust-receiving chamber, means for applying suction through said filter to said dust-receiving chamber to maintain a desired substantially uniform degree of vacuum in said chambers, continuously operating means for progressively forcing fibres accumulating in said fibre-collecting chamber through said tubular conduit, a hinged valve at the outlet end of said discharge conduit, and adjustable means for causing said valve so to resist the passage of fibres forced therethrough as to condense them sufficiently to prevent admission through them of enough air to substantially reduce the uniform degree of vacuum maintained in said chambers.

9. A receiver for the fibre and dust-laden air of a pneumatic stripper for a carding machine or the like comprising a vertical hermetically sealed casing having an upper fibre-collecting chamber provided with a screen wall and having therebeneath a bottom converging downwardly and communicating with a vertical tubular discharge conduit and providing below said bottom a dust-receiving chamber, means for admitting fibre and dust-laden air to said fibre-collecting chamber, means establishing communication between the dust-receiving chamber and the fibre-collecting chamber through said screen, a filter in said dust-receiving chamber, means for applying suction through said filter to said dust-receiving chamber to maintain a desired uniform degree of partial vacuum in said chambers, a ver-

tical plunger reciprocably mounted in said fibre-collecting chamber having a head movable longitudinally of said tubular discharge conduit, capable upon downward movement of efficiently engaging the fibres accumulating in the fibre-collecting chamber and condensing them in the discharge conduit, means for reciprocating said plunger, and means at the outlet of said conduit for so resisting the passage of the fibres therethrough as to condense them sufficiently to prevent admission through them of enough air to substantially reduce said uniform degree of vacuum maintained in said chambers.

10. A receiver for the fibre and dust-laden air of a pneumatic stripper for a carding machine or the like comprising a vertical hermetically sealed casing having an upper fibre-collecting chamber provided with a screen wall and having therebeneath a bottom converging downwardly and communicating with a vertical tubular discharge conduit and providing below said bottom a dust-receiving chamber, means for admitting fibre and dust-laden air to said fibre-collecting chamber, means establishing communication between the dust-receiving chamber and the fibre-collecting chamber through said screen, a filter in said dust-receiving chamber, means for applying suction through said filter to said dust-receiving chamber to maintain a desired uniform degree of partial vacuum in said chambers, a vertical plunger reciprocably mounted in said fibre-collecting chamber having a head provided with downwardly and outwardly diverging prongs movable longitudinally of said tubular discharge conduit, capable upon downward movement of efficiently engaging the fibres accumulating in the fibre collecting chamber and condensing them in the discharge conduit, means for reciprocating said plunger, and an adjustable yieldable valve at the outlet of said conduit for so resisting the passage of the fibres therethrough as to condense them sufficiently to prevent admission through them of enough air to substantially reduce said uniform degree of vacuum maintained in said chambers.

11. A receiver for the fibre and dust-laden air of a pneumatic stripper for a carding machine or the like comprising a vertical hermetically sealed casing having an upper fibre-collecting chamber provided with a screen wall, a door in said chamber below said screen wall, the said chamber having a bottom below said screen wall converging downwardly toward and below said door and communicating with a vertical tubular discharge conduit, a dust-receiving chamber below said bottom, means for admitting the fibre and dust-laden air to the fibre-collecting chamber, means for establishing communication between the dust-receiving chamber and the fibre-collecting chamber through said screen, a filter in said dust-receiving chamber, means for supplying suction through said filter to maintain a desired uniform degree of vacuum in said chambers, a vertical plunger reciprocably mounted on said door in the fibre-collecting chamber in axial alinement with said tubular discharge conduit having a head movable longitudinally of said discharge conduit capable upon downward movement of effectively engaging the fibre accumulating in the fibre-collecting chamber and condensing them in said discharge conduit, means for reciprocating said plunger, and an adjustably yieldable valve at the outlet of said conduit for so resisting the passage of the fibres therethrough as to condense them sufficiently to prevent ad-

mission through them of enough air to substantially reduce said uniform degree of vacuum maintained in said chambers.

12. A receiver for the fibre and dust-laden air of a pneumatic stripper for a carding machine or the like comprising a vertical hermetically sealed casing having an upper fibre-collecting chamber provided with a screen wall, a door in said chamber below said screen wall, the said chamber having a bottom below said screen wall converging downwardly toward and below said door and communicating with a vertical tubular discharge conduit, a dust-receiving chamber below said bottom, means for admitting the fibre and dust-laden air to the fibre-collecting chamber, means for establishing communication between the dust-receiving chamber and the fibre-collecting chamber through said screen, a filter in said dust-receiving chamber, means for supplying suction through said filter to maintain a desired uniform degree of vacuum in said chambers, a vertical plunger reciprocably mounted on said door in the fibre-collecting chamber in axial alinement with said tubular discharge conduit having a head movable longitudinally of said discharge conduit capable upon downward movement of effectively engaging the fibre accumulating in the fibre-collecting chamber and condensing them in said discharge conduit, means for including an electric motor mounted on said door, for reciprocating said plunger, a counterweighted valve hingedly mounted upon the outlet of said conduit, and means for adjusting said counterweight to cause said valve so to resist the passage of fibres therethrough as to condense them sufficiently to prevent admission through them of enough air to substantially reduce said uniform degree of vacuum maintained in said chambers.

13. A receiver for the fibre and dust-laden air of a pneumatic stripper for a carding machine or the like comprising a vertical hermetically sealed casing having an upper fibre-collecting chamber provided with a screen wall and having therebeneath a bottom converging downwardly and communicating with an horizontal tubular discharge conduit extending through the wall of said casing, and provided below said bottom and discharge conduit with a dust-receiving chamber, means for admitting the fibre and dust-laden air into said fibre-collecting chamber, means for establishing communications between said dust-receiving chamber and said fibre-collecting chamber through said screen, means for applying suction to said dust-receiving chamber to maintain a desired uniform degree of partial vacuum in said chambers, means for continuously and progressively forcing the fibres accumulating in said fibre-collecting chamber through said discharge conduit, and a yieldable valve at the outlet end of said discharge conduit for so resisting the passage of the fibres therethrough as to condense them sufficiently to prevent admission of enough air therethrough to substantially reduce the uniform degree of partial vacuum maintained in said chambers.

14. A receiver for the fibre and dust-laden air of a pneumatic stripper for a carding machine or the like comprising a vertical hermetically sealed casing having an upper fibre-collecting chamber provided with a screen wall and having therebeneath a bottom converging downwardly and communicating with an horizontal tubular discharge conduit extending through the wall of said casing and provided below said bottom and

11

discharge conduit with a dust-receiving chamber, a filter in said dust-receiving chamber, means for admitting the fibre and dust-laden air into said fibre-collecting chamber, means for establishing communication between said dust-receiving chamber and said fibre-collecting chamber through said screen, means for applying suction to said dust-receiving chamber through said filter to maintain a desired uniform degree of partial vacuum in said chambers, a screw propeller fitting said discharge conduit, means for rotating said screw propeller continuously and progressively to force the fibres accumulating in said fibre-collecting chamber through said discharge conduit, and an adjustable yieldable valve mounted upon the outlet end of said discharge conduit for so resisting the passage of the fibres therethrough as to condense them sufficiently to permit admission of enough air therethrough to substantially reduce the uniform degree of partial vacuum maintained in said chambers.

15. A receiver for the fibre and dust-laden air of a pneumatic stripper for a carding machine or the like comprising a vertical hermetically sealed casing having an upper fibre-collecting chamber provided with a screen wall and having therebeneath a bottom converging downwardly and communicating with an horizontal tubular discharge conduit extending through the wall of said casing and provided below said bottom and discharge conduit with a dust-receiving chamber, a filter in said dust-receiving chamber, means for admitting the dust-laden air into said fibre-collecting chamber, means for establishing communication between said dust-receiving chamber

5

and said fibre-collecting chamber through said screen, means for applying suction to said dust-receiving chamber through said filter to maintain a desired uniform degree of partial vacuum in said chambers, a screw propeller fitting said discharge conduit, means for rotating said screw propeller continuously and progressively to force the fibres accumulating in said fibre-collecting chamber through said discharge conduit, a valve 10 pivotally mounted upon the outlet end of said conduit having an arm extending outwardly therefrom, and a counterweight adjustably mounted on said arm adapted to cause said valve so to resist the passage of fibres through said conduit as to condense them sufficiently to permit admission of enough air therethrough to substantially reduce the uniform degree of partial vacuum maintained in said chambers.
